[57] CLAIM

The ornamental design for the pillow, as shown and described.

DESCRIPTION

FIG. 1 is a top, front and right side elevational view of a pillow showing my new design;

FIG. 2 is a right side elevational view thereof, the left side being a mirror image of that shown;

FIG. 3 is a top plan view thereof, the bottom being a mirror image of that shown; and

FIG. 4 is a vertical cross-sectional view thereof, taken along line 4—4 of FIG. 3.
